UNITED STATES PATENT OFFICE.

DE LOS E. HIBNER AND FREDERICK W. LINAKER, OF DUBOIS, PENNSYLVANIA, ASSIGNORS TO THE VULCAN SOOT CLEANER COMPANY OF PITTSBURG, PA., OF DUBOIS, PENNSYLVANIA, A CORPORATION OF NEW JERSEY.

BOILER-FLUE-CLEANER SYSTEM.

1,041,080.

Specification of Letters Patent.

Patented Oct. 15, 1912.

Application filed April 27, 1912. Serial No. 693,596.

To all whom it may concern:

Be it known that we, DE LOS E. HIBNER and FREDERICK W. LINAKER, (1) a citizen of the United States and (2) a subject of the King of England, residing at Dubois, in the county of Clearfield and State of Pennsylvania, have invented certain new and useful Improvements in Boiler-Flue-Cleaner Systems, of which the following is

10 a specification.

This invention relates to certain new and useful improvements in boiler flue cleaner systems, and relates more particularly to that type of flue cleaners in which a fluid, such as steam, is employed as a cleaning agent for removing soot from the flues, and for preventing an accumulation of soot on the flues.

The present invention is an improvement 20 upon flue cleaners of the type shown, described, and claimed in Letters Patent #705,912, granted July 29, 1902 to William Eichelberger, soot cleaners for boilers; Letters Patent #801,858, Oct. 17, 1905 to William Eichelberger, for soot cleaners for boilers; Letters Patent #984,919, granted Feb. 21, 1911 to De Los E. Hibner, boiler flue cleaner systems, and upon the flue cleaner systems shown and described in application Serial #670,608 of De Los E. Hibner, and application Serial #673,643 of James Moore, for improvement in boiler flue cleaner systems.

The present invention is more specifically, 35 an improvement in the systems shown and described in the Hibner application #670,608 and the Moore application #673,643 above referred to, and has for its main object to provide means whereby the 40 discharge nozzles of the distributing pipes will be guided during the rotation of the distributing pipe in such manner that the cleaning agent will be projected on a line at an oblique angle to the axis of the distributing pipe at all times except when the 45 nozzle is at a right angle to the axis of such distributing pipe.

It is a further object of the present invention to provide, in a flue cleaner system 50 of the type particularly referred to above, means for guiding the discharge end of the nozzle or nozzles carried by the distributing pipe so that the cleaning agent will be pro-

jected on the desired oblique line between the tubes of the boiler.

55

It is a further object of the present invention to provide means in a flue cleaner system involving rotatable distributing pipes for maintaining the nozzle or nozzles carried by the distributing pipe clear of the tubes or flues of the boiler at all times, thereby preventing any wear of the tubes or abrasion of the same by the nozzles.

It is a still further object of the present invention to provide a flue cleaner system 65 of the type particularly referred to which can be readily adapted to any of the different types of water tube boilers, and it is a still further object to provide in a flue cleaner system of this type, for such an arrangement and construction as will materially decrease the number of distributing pipes generally required, thus greatly simplifying and cheapening the cost of installation, as well as cost for maintenance of the 75 system.

Still further objects of the present invention will appear hereinafter as the practical embodiment which has been chosen for the purpose of illustration, is more fully described in detail and then claimed, and in describing the invention in detail, reference will be had to the accompanying drawings forming a part of this specification, and wherein like numerals of reference will be 85 employed to designate like parts throughout the different views of the drawings, in which:-

Figure 1 is a view in elevation with portions of a boiler setting broken away and 90 portions in section, a flue cleaner in accordance with the present invention being shown as applied in position with respect to the water tubes of the boiler. Fig. 2 is a sectional elevation of a boiler and its setting, 95 partly broken away, a flue cleaner system in accordance with this invention, being shown as applied thereto. Fig. 3 is an enlarged detail perspective view of one form of device for guiding the discharge end of 100 the distributing pipe nozzle, the view illustrating a portion of a distributing pipe, and also showing the guiding means for the discharge nozzle as being supported from one of the water tubes. Fig. 4 is a transverse 105 vertical sectional view of the same, the view

being practically on line 4—4 of Fig. 5 but with the discharge nozzle in side elevation. Fig. 5 is a front elevation of the said nozzle guiding device or member. Fig. 6 is a central longitudinal sectional view of the discharge nozzle. Fig. 7 is a longitudinal sectional view of the discharge nozzle taken on line 7—7 of Fig. 6. Fig. 8 is a transverse vertical sectional view of the discharge nozzle taken on the line 8—8 of Fig. 6, and, Fig. 9 is a detail view of a modified form of the device for guiding the discharge end of the nozzle during rotation of the distributing pipe.

In order to clearly illustrate an application of our invention to a water tube boiler, we have chosen to show it as applied to a water tube boiler of the well-known Babcock and Wilson type, but it will be understood that the system is alike applicable to all the different types of water tube boilers, such changes as may be made being wholly as to position and location, and not in any principle of operation of the device.

In the herein illustrated embodiment of the invention, we have also shown the distributing pipes as connected up to a feed pipe 10 which is usually arranged outside of the boiler setting, and which feed pipe is connected to the distributing pipes by branch pipes 11 in a manner clearly shown in the above referred to applications of De Los E. Hibner and James Moore and in certain of the patents also above referred to. The said feed line and branch pipes are provided with the shut-off valves, drain valves, vacuum preventing devices, etc., all as clearly illustrated in Patent #984,919 above referred to, and which is not necessary to herein describe in detail.

As heretofore stated, the distributing pipe or pipes in the present system are adapted to be rotated on their axis or axes, and this rotation may be effected in any suitable manner. We herein show a chain and sprocket for effecting such rotation, but obviously, a handle or lever connected to the distributing pipe, or other equivalent means would perform the same function.

By reason of the means which is provided in the present system for maintaining the discharge end of the nozzle or nozzles of the distributing pipe or pipes at an oblique angle to the axis of the distributing pipe or pipes during the rotation of the latter, the sweep or range covered by the cleaning agent projected from each nozzle is very materially increased, and for this reason a material decrease in the number of distributing pipes required is effected. We have found in practice that by the use of the guiding means for the discharge nozzles, that three of the distributing pipes are sufficient for a boiler of ordinary capacity, whereas a boiler of substantially the same

capacity would require at least double the amount of distributing pipes in order to cover all of the surface of the flues, by reason of the more limited range of the steam projected from each nozzle, due to the restricted oblique angle in which the cleaning agent is projected when the discharge end of the nozzle is at all times in the same relation with respect to the axis of the distributing tube.

In the illustration, two distributing pipes are shown as disposed above the flues, and one beneath the flues, and since our invention in the present instance relates to the maintaining of the desired oblique angle of discharge, a description of the means shown for one distributing pipe will suffice for all.

Reference will therefore be particularly had to Figs. 3 to 9 inclusive of the drawings, it being understood that the distributing pipe or pipes 12 is or are provided with a sprocket and chain or other equivalent means as 14 for revolving the pipe or pipes, such means being located outside the boiler setting in the usual manner. Each distributing pipe is suitably journaled in the front wall of the boiler setting, and since, with the present invention, the distributing pipe is supported at intervals throughout its length, it becomes unnecessary to provide any support for the distributing pipe at its inner end, thus simplifying and cheapening the cost of installation.

In Figs. 3, 4, and 5, a specific form of device for guiding the discharge end of the nozzle or nozzles of the pipe is illustrated, and in Figs. 3 to 8, a specific form of nozzle is illustrated, it being understood however, that this construction may be changed or altered as may be desired, without departing from the broad idea of maintaining the discharge end of the nozzle at the desired oblique angle to the axis of the distributing pipe.

As we have practiced the invention, we have provided the distributing pipe 12 with a plurality of sectional nozzles so disposed as to project the cleaning agent in the spaces between the rows of tubes, it being understood that the nozzles carried by each distributing pipe are so arranged with respect to the circumference of said pipe or pipes as to provide for the desired lines of projection from the distributing pipe or pipes, that is, it will be obvious that the nozzles do not all project from their distributing pipes in a straight line with the pipe.

The nozzle as herein illustrated is formed or provided with a universal or swivel joint intermediate its inlet end and its discharge end. The inlet end of the nozzle is tapped into the distributing pipe and is designated as 14', the discharge end or nipple of the nozzle being designated as 15. The portion 14' of the nozzle has a boss or a body 16 in

which the hub or bearing member 17 of the discharge nipple 15 is received, and wherein it is secured as by means of a nut 18 which constitutes a seat for one end of the bearing 17, and which nut may be locked in position as by a set screw 19, or in any other suitable manner. The parts 14', 16, and 15 are ported, so that the ports therein register at all times, providing a continuous

19 passage way from the distributing pipe through the nozzle, such passage way however, being an irregular one instead of upon a straight line. It is to be understood that this merely illustrates one form of a nozzle

20 which, when the distributing pipe is rotated, may have its discharge end retained in such position as to discharge at the desired oblique angle with respect to the axis of the distributing pipe, and we therefore do not

21 claim the specific construction of nozzle herein shown and above described, but illustrate it merely as one form of device which can be advantageously used to accomplish the purpose of our invention.

22 The means herein illustrated in Fig. 3 for guiding the discharge end of the nozzle consists of a guide member designated generally by the reference numeral 20, and which embodies two spaced side plates 21 and 22

23 respectively, which are practically of horseshoe form, being held in spaced relation to each other by connecting bars as 23, or in any other desired manner, the space at the ends of the plates being preferably closed,

24 since such construction provides for a limiting of the rotary movement which can be given to the distributing pipes, and thereby obviates any danger of these pipes being rotated into a position where the steam 25 would be projected into space where it could perform no useful function.

The discharge or nipple end 15 of the nozzle is received in the guide-way provided by the spaced plates 21, 22 of the guide herein illustrated, and it will be obvious that as the distributing pipe 12 is rotated, the nipple or discharge end 15 of the nozzle will be held in such guide-way, the degree of the oblique angle of the nipple with respect to the axis of the distributing pipe changing as the distributing pipe is rotated but an oblique angle being maintained at all times until the nozzle reaches an angle at direct right angles to the axis of the distributing pipe.

We have herein shown the guide member 20 in Figs. 3, 4, and 5 as being supported directly upon one of the water tubes 24, by means of clamp members 25 which after 26 being clamped around the water tube are suitably fastened thereto in any desired manner. We preferably, when the form of guiding member illustrated in Figs. 3 to 5 is employed, provide the same at its lower 27 end, with a depending supporting arm 26

which rests upon the water tube 24 directly below that water tube to which the guide member is attached. This supporting arm, while acting as an additional support for the guide member, obviating danger of the latter shifting its position relative to the distributing pipe, also serves the function of positioning the guide member so that the oblique angle of projection of the cleaning agent with respect to the axis of the distributing pipe is assured.

28 Instead of employing a guide plate of the form shown in Figs. 3 to 5, the same function may be obtained by the device illustrated in Fig. 9, in which we provide on the nipple 15' of the nozzle, a hook member 27 which engages over a guide plate 28, the nipple end of the nozzle in this construction being maintained at the oblique angle by reason of the hook member riding around 29 on the guide plate 27 as the distributing pipe is revolved.

30 It is to be understood that while we have herein shown the means employed for maintaining the nipple or discharge end of the nozzle at an oblique angle to the axis of the distributing pipe, as being supported by the water tubes of the boiler, yet it will be evident that the means employed for guiding

31 the discharge end or nipple of the nozzle or nozzles may be as readily supported wholly independent of the water tubes, and we therefore do not wish to confine ourselves to any construction in which the water tubes 32 act as the support for the guiding means.

33 Where a guiding means such as herein illustrated and described is employed, it will be observed that in addition to its designed function of maintaining a desired oblique angle between the nipple and the axis of the distributing pipe, it also serves to prevent the nozzle from contacting at any time with the water tubes adjacent thereto, obviating any danger of wearing or otherwise damaging the tubes due to their being struck by 34 the nozzles during rotation of the distributing pipes.

We also desire to call attention to the fact that the supporting arm 26, in the use of a guiding member such as illustrated in Fig. 3, fixes the oblique line in the particular boiler to which the device is to be applied, as will be evident by reference to Fig. 4 of the drawings, some water tube boilers having their tubes so disposed that the tubes of one course are staggered with respect to the tubes or flues of an adjacent course.

35 With a construction such as above described, it will be clear that as the distributing pipe or pipes are rotated, that the discharge or nipple end of the nozzle is maintained at the oblique angle which will cause the projection of the cleaning agent to be on a line that passes through between the tubes in such manner as to effectually clean 36

the latter of any accumulation of soot thereon. It will be understood that the nozzles are so disposed or arranged on the distributing pipe or pipes, that the jet from one nozzle will not intersect the jet from another nozzle, the cleaning agent projected from one nozzle being therefore permitted to expand its full force in the cleaning operation.

10 While we have described and illustrated details of construction whereby the objects of the invention may be attained, and as the invention has been practiced by us, yet we do not herein confine ourselves to any of these details of construction, since our invention in the present case resides broadly in the principle of providing means for maintaining the projection of the cleaning agent at the correct oblique angle to the axis 15 of the distributing pipe throughout the arc of rotation.

Having fully described our invention, what we claim as new and desire to secure by Letters Patent of the United States is:—

25 1. In a flue cleaner system, a distributing pipe mounted for rotation in proximity to the water tubes of a boiler, means for supplying said pipe with steam, projecting nozzles carried by said pipe, and means whereby the discharge ends of said nozzles are maintained at an oblique angle to the axis 30 of the distributing pipe while the inlet ends of the nozzles describe an arc of a circle on lines at right angles to the axis of said pipe 35 while the latter is being rotated.

2. In a flue cleaner system, a distributing pipe mounted for rotation in proximity to the tubes of a boiler, a nozzle carried by said pipe, and means whereby the oblique angularity of the discharge end of the nozzle 40 with respect to the axis of the distributing pipe is maintained while the distributing pipe is being rotated and the inlet end of the nozzle is describing an arc of a circle on 45 lines at right angles to the axis of the distributing pipe.

3. In a flue cleaner system, a rotatably mounted* distributing pipe having connection with a steam supply, flexible nozzles 50 carried by the distributing pipe and projecting therefrom, and means whereby the discharge ends of said nozzles are retained at an oblique angle with respect to the axis of the distributing pipe and the inlet ends of 55 said nozzles are describing an arc of a circle on lines at right angles to said distributing pipe during rotation of the latter.

4. In a flue cleaner system, a distributing pipe, a steam feed line for the distributing 60 pipe, and nozzles carried by the distributing pipe capable of having their discharge ends retained in such position that the steam is discharged therefrom during rotation of the distributing pipe in lines at oblique angles 65 to the axis of the distributing pipe, means

for so retaining said discharge ends of the nozzles, the inlet ends of said nozzles describing an arc of a circle on lines at right angles to the axis of the distributing pipe during rotation of the latter.

5. In a flue cleaner system, a rotatably mounted distributing pipe, means for supplying steam to said pipe, and nozzles carried by said pipe which are flexible between the distributing pipe and their outlet ends whereby the outlet ends of the nozzles are retained during rotation of the pipe on lines at an oblique angle to the axis of the distributing pipe.

6. In a flue cleaner system, a plurality of 80 distributing pipes mounted in proximity to the boiler flues and capable of rotation, means for supplying steam to said pipes, and nozzles carried by the pipes and so constructed as to be pliable between their inlet 85 and their discharge ends, whereby said discharge ends are held on lines extending at an oblique angle with respect to the axis of the distributing pipes while the latter are being rotated.

7. In a flue cleaner system, a distributing pipe, and means for rotating said pipe, combined with nozzles carried by the distributing pipe which are pliable between their inlet and discharge ends, and means for retaining the discharge ends of the nozzles on lines extending at an oblique angle to the axis of the distributing pipe while the latter is being rotated.

8. In a flue cleaner system, a rotatably mounted distributing pipe, means for supplying steam to said pipe, nozzles carried by the distributing pipe and pliable intermediate their inlet and discharge ends, and means for guiding the discharge ends of 100 said nozzles during rotation of the pipe to retain said discharge ends on lines extending at oblique angles to the axis of the distributing pipe.

9. In a tube cleaner system, a distributing 110 pipe mounted for rotation in proximity to the water tubes of a boiler, nozzles projecting from said pipe and lying between adjacent tubes that are on the same plane, and means for guiding the discharge ends of 115 said nozzles and holding same out of contact with the boiler tubes as the distributing pipe is rotated.

10. In a tube cleaner system, a distributing pipe mounted for rotation in proximity 120 to the water tubes of a boiler and connected to a steam supply, a plurality of nozzles projecting from said pipe and each comprising an inlet and a discharge section, said nozzles adapted to project the steam between 125 the tubes on lines at an oblique angle to the axis of the distributing pipe, and means for guiding the discharge section of each nozzle whereby said lines of oblique angle are maintained during rotation of the pipe.

11. In a tube cleaner system, a distributing pipe mounted for rotation in proximity to the water tubes of a boiler and connected to a steam supply, a plurality of nozzles carried by said pipe and projecting between adjacent tubes of the boiler, said nozzles swinging with the pipe as the latter is rotated and adapted to project the steam between the tubes on lines at an oblique angle to the axis
5 of the pipe, and means for maintaining the
10

oblique lines of steam discharge throughout the arc of rotation of the pipe.

In testimony whereof we affix our signatures in presence of two witnesses.
